(57) **CLAIM**

The ornamental design for a headgear, as shown and described.

DESCRIPTION

FIG. 1 is a perspective view of headgear showing our new design;

FIG. 2 is a right side view thereof, the left side view being a mirror image thereof;

FIG. 3 is a front view thereof;

FIG. 4 is a rear view thereof;

FIG. 5 is a top view thereof; and,

FIG. 6 is a bottom view thereof.

In the drawings, the broken lines in FIGS. 1–6 depict portions of the design that form no part of the claim.
